IRVING F. WEBB, OF ELIZABETH, NEW JERSEY, ASSIGNOR TO THE SINGER MANUFACTURING COMPANY, A CORPORATION OF NEW JERSEY.

PRESSER-FOOT FOR SEWING-MACHINES.

1,302,998.

Specification of Letters Patent.

Patented May 6, 1919.

Application filed July 15, 1915. Serial No. 39,970.

To all whom it may concern:

Be it known that I, IRVING F. WEBB, a citizen of the United States, residing at Elizabeth, in the county of Union and State of New Jersey, have invented certain new and useful Improvements in Presser-Foots for Sewing-Machines, of which the following is a specification, reference being had therein to the accompanying drawings.

- 10 This invention has for its object to provide a sewing machine presser-foot adapted to readily pass over very heavy and coarse fabrics and particularly adapted to pass over several plies of fabric such as are encountered in stitching the mouths of heavy burlap bags. It also has for its object the construction of a presser-foot which will insure at all times the "chaining off" of the connecting seam between successive articles as 15 they pass beneath the stitch-forming mechanism particularly just prior to and at the beginning of the entrance of the heavy fabric between the presser-foot and the usual work-supporting element.
- 20 A further object of the invention is to shield the needle from penetrating coarse and bulky material which may be deflected over the presser-foot, so as to obviate liability to breakage of the needle. A further 25 object of the invention is to prevent accidental injury of the fingers of the operator by the needle.

According to the present invention the presser-foot is constructed with a shank portion carrying at its lower end a tilting primary or rearward foot-plate or piece. Pivoted upon the forward portion of the primary foot-plate and arranged in advance thereof, is a secondary or forward foot-plate 30 or piece which is spring-pressed to retain it in normal relation with the primary foot-plate so that the treads of both foot-plates will be substantially flush at their adjacent ends. Rigid with the secondary foot-plate 35 is a lug embracing its pivotal support with the primary foot-plate and overlying the tread portion of the latter. As the fabric approaches the secondary foot-plate the latter is slightly tilted until the fabric has 40 almost reached the inner end of the secondary foot-plate and is about to be entered by the needle when a further movement of the fabric brings it in contact with the primary foot-plate which will also be tilted so 45 that its work-engaging edge will be raised.

50 into substantial alinement with that of the secondary foot-plate but its heel will still remain in contact with the throat-plate, which is necessary to provide sufficient pressure upon the needle- and looper-threads to insure the proper "chaining off" between successive articles being stitched. The primary foot-plate remains in tilted position until one or more stitches have been completed when, by the continued travel of the 55 material, the presser-foot will ride upon the advance end of the material in the usual manner to allow unobstructed passage of the latter. The secondary foot-plate is yieldingly forced downward by a spring into 60 flush relation with the primary foot-plate.

65 In the preferred form of the improvement the secondary foot-plate is provided with a guard which extends above the needle in extreme retracted position of the needle-point from the throat-plate and shields it from penetration of the material when accidentally deflected over instead of under the presser-foot, which sometimes happens under 70 certain conditions when stitching heavy burlap or canvas bags. This guard is preferably carried by the secondary foot-plate and moves with the latter when tilted.

75 As represented in the drawings, Figure 1 is a perspective view of a portion of a sewing machine head showing the presser-foot, 80 with the material passing under the secondary foot-plate which is slightly tilted, and the needle entering the material; Fig. 2 is an elevation showing the presser-foot, 85 partly in section, with the fabric passing beneath the secondary foot-plate and coming in contact with the primary foot-plate but with the heel of the latter still resting upon the throat-plate. Fig. 3 is a detail perspective view of the secondary foot-plate with 90 the guard; and Figs. 4 and 5 are similar detail views of the presser-foot shank and the primary foot-plate, respectively.

95 As represented in the drawings, the improvement is embodied in the well known Singer machine for stitching bags comprising the work-plate 1, sustaining the throat-plate 2 having the usual openings to receive the feed-dog 3. Above the work-plate 1 is 100 the usual bracket-arm 4 having the head 5 in which is suitably journaled the presser-bar 6 and needle-bar 7 carrying the needle 8.

105 Depending from the presser-bar 6 and secured thereon by the usual fastening screw 9 110

is the presser-foot comprising the shank portion 10 having the primary or rearward foot-plate 11 pivotally secured to the shank by the screw 12. Rising from the primary 5 or rearward foot-plate 11 are the spaced ears 13 forming a channel to receive the presser-foot shank 10. These ears, which prevent lateral displacement of the primary foot-plate with respect to the shank, are suitably 10 apertured to receive the fulcrum-screw 12 which is screw-threaded into one of the ears to retain it in position.

Also journaled in the ears 13 of the foot-plate 11, is a second fulcrum-pin 14 which passes through an aperture 15 of the lug 16 of the secondary or forward foot-plate 17 for which it forms a pivotal support. The fulcrum-pin 14 is retained in position by the set-screw 18 entering a suitably 20 threaded aperture 19 in the lug 16 and impinging against a flat seat 20 formed upon the fulcrum-pin. The base of the lug 16 is formed with a projection 21 whose lower face is flush with the upper face of the secondary foot-plate 17. This projection extends over and rests upon the inner edge of the primary foot-plate 11 against which it is normally retained by a spiral spring 22 surrounding the free end of the fulcrum-pin 14. One end of the spring 22 is seated in a recess 23 cut in the ear 13 of the primary foot-plate 11 while the other end of the spring rests in a groove 24 cut into the upper face of the secondary foot-plate 17. 30 The spring 22 retains the primary and secondary foot-plates 11 and 17 in normal relation so that the treads of both foot-plates will be substantially flush at their adjacent edges.

40 As represented in Fig. 1, the material *a* has come in contact with the secondary foot-plate 17 and has just been entered by the needle 8 and has caused a slight tilting of said foot-plate without disturbing the normal position of the primary foot-plate 11 whose tread still rests upon the throat-plate 2 so as to maintain its pressure upon the chain of threads extending from the previous article stitched. As the material is 45 advanced by the feeding mechanism and one or more stitches made therein, the secondary foot-plate 17 will be tilted and through its pivotal and yielding connection, by means of the fulcrum-pin 14 and spring 22, with the primary foot-plate 11, the work-engaging edge of the latter will be slightly raised but the heel of the primary foot-plate 11 will remain in contact with the throat-plate 2. Through the fulcrum-pin and its co-operating spring, connecting the primary and secondary foot-plates, the primary foot-plate 11 is forcibly lifted or raised until the edge of its work-engaging face is in substantial alignment with that of the secondary foot-plate 17. The latter conditions, are clearly 55

represented in Fig. 2, which shows that, although several stitches have been made, the material has not been sufficiently advanced to raise the heel of the primary foot-plate 11 out of contact with the throat-plate 2 70 which still exerts a pressure upon the threads, insuring a proper tightening of the stitches at the beginning of the stitching operation. A further advance of the material causes the primary foot-plate to ride upon 75 the material in the usual manner.

In order to protect the needle 8 and shield its point from contact with the material when accidentally deflected over instead of under the presser-foot, a guard 25 is applied 80 to the latter. It comprises in its preferred form a U-shaped wire member with its closed portion secured by soldering or otherwise to the toe-portion of the secondary foot-plate 17 and presenting an upper surface 85 or edge extending from front to rear of and beyond the path of the needle in a direction preferably substantially parallel with the tread portion of the foot-plate 17 with its depending arms secured to the latter adjacent the seat 21 and beyond the needle aperture 26. The guard 25 shields the needle point when moved to its extreme retracted position above the presser-foot, as clearly shown by dotted lines in Fig. 2. The upper 90 edge of the guard thus affords a work-supporting guide or shield disposed throughout its length above the highest position of the needle point so as to operate with the needle-blade or needle-bar to confine material presented above the presser-foot to a position above the needle point. With the common form of presser-foot, as heretofore used, it sometimes happens, particularly when stitching torn or defective burlap bags, that the 95 material will ride over the toe of the presser-foot and catch thereon so as to necessitate the stopping of the machine in order to remove the material, with a consequent loss of time. With the presser-foot of the present 100 improvement, this difficulty is fully overcome by the guard which prevents material riding over the toe of the foot from catching thereon, while shielding the fingers of the 105 operator from injury by the needle. 110

Having thus set forth the nature of the invention, what I claim herein is:—

1. A presser-foot comprising a shank portion, a plurality of foot-plates mounted thereon for movement relative thereto, a plurality of fulcrum-pins upon which said foot plates are respectively mounted, and means carried by one of said foot-plates and acting when said foot-plate rises in passing over a thickened portion of material to raise 115 the work engaging edge of the other foot-plate.

2. A presser-foot comprising a shank portion, a plurality of foot-plates mounted thereon one in advance of the other for 120

movement relative thereto, a plurality of fulcrum-pins upon which said foot-plates are respectively mounted, and means carried by one of said foot-plates and acting when 5 said foot-plate rises in passing over a thickened portion of material to raise the work-engaging edge of the other foot-plate.

3. A presser-foot comprising a shank-portion, a plurality of foot-plates, a plurality 10 of fulcrum-pins upon which said foot-plates are respectively mounted, means carried by one of said foot-plates for tilting another of said foot-plates, and means including a spring secured to one of said plates to retain them in flush relation. 15

4. A presser-foot comprising a shank-portion, a primary foot-plate mounted thereon, a secondary foot-plate mounted upon said primary foot-plate, and means carried by 20 said secondary foot-plate for tilting said primary foot-plate.

5. A presser-foot comprising a shank-portion, a primary foot-plate mounted thereon, a secondary foot-plate mounted upon said 25 primary foot-plate and means including a spring interposed between said foot-plates for tilting the primary foot-plate relatively to the secondary foot-plate.

6. A presser-foot comprising a shank-portion, a primary foot-plate mounted thereon, a secondary foot-plate mounted upon said primary foot-plate and a spring for normally maintaining said foot-plates in flush 30 relation upon the work but adapted to tilt 35 the primary foot-plate when passing over varying thicknesses of material.

7. A presser-foot comprising a shank-portion,

40
tion, a primary foot-plate mounted thereon, a secondary foot-plate mounted upon said primary foot-plate, a guard movable with said secondary foot-plate, and means carried by one of said foot-plates for tilting the other foot-plate.

8. The combination with a reciprocating 45 needle, a work-supporting element, a presser-foot shank and a plurality of foot-plates mounted upon said shank, of a guard carried by one of said foot-plates having a work-supporting upper surface disposed throughout its length above the extreme position of retraction of the needle-point from the work-supporting element. 50

9. The combination with a reciprocating 55 needle, and a work-supporting element, of a presser-foot shank, a primary foot-plate mounted upon said shank, a secondary foot-plate mounted upon said primary foot-plate, and a guard carried by one of said foot-plates and extending above the work-supporting element beyond the extreme position of retraction of the needle-point from the work-supporting element. 60

10. A presser-foot comprising a shank portion and a plurality of foot plates arranged one behind the other, the rearward 65 plate having a direct pivotal connection with the shank-portion and the forward plate having a pivotal connection with the rearward plate by which said connection is sustained. 70

In testimony whereof I have signed my name to this specification.

IRVING F. WEBB.
